UNITED STATES PATENT OFFICE.

LEON DREYFUS, OF NEW ORLEANS, LOUISIANA.

EAR-WIRE FOR EAR-RINGS.

SPECIFICATION forming part of Letters Patent No. 355,007, dated December 28, 1886.

Application filed August 3, 1886. Serial No. 209,858. (No model.)

To all whom it may concern:

Be it known that I, LEON DREYFUS, of New Orleans, in the parish of Orleans and State of Louisiana, have invented certain new and useful Improvements in Ear-Wires for Ear-Rings, 5 of which the following is a specification.

This invention relates to certain new and useful improvements in the ear-wires by means of which ear-rings are suspended from the lobe 10 of the ear.

The object of my invention is to provide a new and improved ear-wire from which the drop or pendant forming the ear-ring hangs vertical at all times.

15 The invention consists in an ear-wire provided with an angle or bend toward the rear in its upper part, as will be fully described and set forth hereinafter, and pointed out in the claims.

20 In the accompanying drawings, Figure 1 is a side view of an ear-ring provided with an ear-wire used heretofore. Fig. 2 is a side view of an ear-ring provided with my improved ear-wire.

25 Similar letters of reference indicate corresponding parts.

The ear-wire A, Fig. 1, as made heretofore, is provided with a ring, B, from which the drop or pendant C is suspended. The weight 30 of the drop tends to swing the lower end of the ear-wire A in the direction of the arrow a', Fig. 1, bringing the ear-wire into the position shown in dotted lines in Fig. 1, which is very objectionable. In order to avoid this objectionable feature, I make my improved ear-wire

35 M (shown in Fig. 2) in the following manner: From the point at which the eye or ring N for fastening the drop or pendant O is secured on the ear-wire the ear-wire extends to the rear

40 at right angles to the plane in which the drop is to hang, and is then provided with a bend, P, from which the wire extends upward, as at Q, and is then bent down forming the spring-catch. From the eye or ring M the other part or arm

45 of the ear-wire extends downward in front of the lower part of the lobe of the ear, and has

a hook, R, at its end, with which hook the free end of the ear-wire is connected for the purpose of keeping the wire closed. The straight part of the ear-wire, extending from the eye 50 N to the bend P, is passed through the aperture in the lobe of the ear, and the part Q extends upward on the rear side of the lobe. The weight of the drop or pendant acting on the ear-wire presses the part Q against the rear 55 side of the lobe and prevents tilting of the ear-wire—that is, the ear-wire cannot be brought into the position shown in dotted lines in Fig. 1. In the old construction (shown in Fig. 1) the wire, after it has passed through the aperture in the lobe of the ear, extends downward, whereas in my improved construction the ear-wire extends upward after having passed through the aperture in the lobe of the ear, and forms an abutment resting against the rear 60 side of the lobe.

Any kind or style of pendant or ear-ornament of any desired material can be fastened on the improved ear-wire.

Having thus described my invention, I claim 70 as new and desire to secure by Letters Patent—

An ear-wire for ear-rings having a straight part, at one end of which the ornament is fastened to the ear-wire, an upwardly-projecting 75 part at the opposite end of the said straight part, and a downwardly-projecting spring part extending down from the upwardly-projecting part, and with an arm extending downward from the point at which the ornament is fastened, said arm being provided at its lower end with a hook for engagement with the spring 80 end of the wire, substantially as shown and described.

In testimony that I claim the foregoing as my 85 invention I have signed my name in presence of two subscribing witnesses.

LEON DREYFUS.
